United States Patent Office

Des. 183,660
Patented Oct. 7, 1958

183,660

TABLE

Lavinia J. Palmer, Lawrenceville, Va.

Application July 24, 1956, Serial No. 42,361

Term of patent 14 years

(Cl. D33—14)

FIG. 1

FIG. 2

FIG. 3

Fig. 1 is a perspective view of a table showing my new design;

Fig. 2 is a bottom view with the parts in folded position; and

Fig. 3 is an edge view looking from the left of Fig. 2.

The dominant features of my design reside in those portions shown in full lines on the drawing.

I claim:

The ornamental design for a table, as shown and described.
